ATTORNEY

UNITED STATES PATENT OFFICE.

HENRY LEWIS GUY, OF MANCHESTER, ENGLAND, ASSIGNOR TO WESTINGHOUSE ELECTRIC & MANUFACTURING COMPANY, A CORPORATION OF PENNSYLVANIA.

HEATER.

Application filed July 18, 1924, Serial No. 726,777, and in Great Britain August 17, 1923.

This invention relates to that type of apparatus comprising a steam actuated ejector in combination with a feed water heater, and it has for its object to provide an improved construction and arrangement of apparatus of this type. To this end the invention consists in arranging the ejector with its diffuser projecting axially into the interior of the tube nest of a feed water heater of the surface type. Preferably the diffuser projects into a space left for its reception in the center of the tube nest and is arranged to discharge into a tubular baffle adapted to convey the discharged vapors to one end of the tube nest through which they are caused to flow in a tortuous path by a convenient arrangement of baffles. The feed water heater may be of any suitable construction but is preferably arranged vertically with both inlet and outlet chambers for the feed water at the lower end, these chambers being connected by field tubes or by ordinary tubes communicating with a suitable distribution box or header at the upper end of the heater. The invention is applicable to apparatus of both the single and multi-stage type and in its latter application the ejectors of the several stages are arranged in combination with separate feed water heaters or with separate stages of a single heater, the ejector of the second and any subsequent stage being adapted to entrain non-condensable gases from the feed water heater of the previous stage or from the previous stage of the same feed water heater.

By way of example, reference will now be made to the accompanying drawing which is a vertical section through a two-stage apparatus constructed in accordance with the invention.

The apparatus illustrated comprises feed water heaters 1 and 2 each of which comprises a substantially cylindrical casing 3 provided with water inlet ports 4, 4' and with outlet ports 5 and 5', a steam inlet port 6, a drain port 7, and a port 8 for the discharge of non-condensable gases, this latter being omitted from the illustration of the heater 2. The casing 3 is divided into compartments 9, 10 and 11 by tube plates 12 and 13 in which are secured the lower ends of the inner and outer tubes 14 and 15 of field tubes composing the tube nest 16, the field

tubes being further supported by a perforate 55 plate or bracket 17 and baffles 18 suitably mounted in the interior of the casing 3.

Mounted on the top of the feed water heaters 1 and 2 are ejectors 19 and 20 of known construction the diffusers 21 of which 60 are connected with tubular baffles 22. The said diffusers project through the steam inlet ports 6 of their respective feed water heaters into spaces left for their reception at the centers of the tube nests 16.

The water outlet port 5 of the heater 1 is connected with the water inlet port 4' of the heater 2 and the port 8 of the heater 1 is connected with the entraining inlet 23 of the 65 ejector 20.

In operation, fluid discharged from the diffuser 21 of the ejector 19 enters the tubular baffle 22 and is conveyed by the latter to the lower part of the tube nest 16 from which it flows upwardly in contact with the tubes 15, being constrained to follow a tortuous path, as indicated by the arrows, by the baffles 18. Feed water is admitted to the compartment 9 of the heater 1 through the inlet port 4 and flows upwardly through the tubes 14 and downwardly through the tubes 15 to the compartment 10 from which it flows by way of the outlet port 5 of the heater 1 and inlet port 4' of the heater 2 to the compartment 10 of the latter. During 70 its passage through the tube nest of the heater 1 the feed water condenses the condensable vapors discharged from the ejector 19, the condensate being drained away through the port 7. The non-condensable 75 gases discharged by the ejector 19 pass through the port 8 of the heater 1 to the ejector 20 where they are entrained by the motive fluid of the latter and pass downwardly through the diffuser 21 and baffle 22 to the lower part of the tube nest 16 of the heater 2.

From here they pass upwardly in a tortuous path as in the heater 1, the condensable vapors being condensed by the cooling action of the feed water which passes 80 upwardly from the chamber 10 of the heater 2 through the tubes 15 and downwardly through the tubes 14 to the chamber 9 from which it passes to the boiler or to the next heater of the series by way of the outlet port 105 5'. Vapors condensed in the tube nest of the heater 2 are drained away through the port 7 while non-condensable gases pass

away to the atmosphere through a port, not shown, corresponding to the port 8 of feed heater 1.

With the arrangements described above 5 and with any other constructional form of the invention it is possible to employ straight diffusers with the result that losses incidental to the use of curved diffusers such as have previously been employed in arrangements 10 of this kind are obviated. It is also possible to recover substantially the whole of the heat from the ejectors and to employ a neater and simpler pipe arrangement.

While I have shown my invention in but 15 one form, it will be obvious to those skilled in the art that it is not so limited, but is susceptible of various other changes and modifications, without departing from the spirit thereof, and I desire, therefore, that 20 only such limitations shall be placed thereupon as are imposed by the prior art or as are specifically set forth in the appended claims.

What I claim is:

25 1. A device of the type described, comprising a shell, a nest of tubes within the shell, said nest being arranged to provide a longitudinally extending space therein, connections for passing circulating media 30 through the tubes, an ejector associated with one end of said nest of tubes, the diffuser of said ejector extending within said space, and a baffle for directing media discharged from the diffuser through said space.

35 2. A device of the type described, comprising a shell, a nest of tubes within the shell, said nest being arranged to provide a longitudinally extending space therein, connections for passing circulating media 40 through the tubes, an ejector associated with one end of said nest of tubes, the diffuser of said ejector extending within said space, a baffle for directing media discharged from the diffuser through the said space, and a 45 connection on said shell for passing gaseous media from said one end of the nest of tubes.

50 3. A device of the type described, comprising a pair of nests of tubes, each of said nests being arranged to provide a substantially cylindrical space, a shell for each nest of tubes, connections associated with one of the ends of each of said shells for passing circulating media through the tubes, an ejector 55 associated with each of the other of the ends of said nests of tubes, the diffusers of said ejectors extending within the substantially cylindrical spaces, and a connection adjacent said other end of one of said shells 60 for passing gaseous media therefrom.

65 4. A device of the type described comprising a pair of nests of tubes, each of said nests being arranged to provide a substantially cylindrical space, a shell for each nest of 70 tubes, connections associated with one of the

ends of each of said shells for passing circulating media through the respective nests of tubes in series, an ejector associated with each of the other of the ends of said nests of tubes, the diffusers of said ejectors extending within the respective substantially cylindrical spaces, and a connection adjacent one of said other ends of said shells for passing gaseous media therefrom. 75

5. A device of the type described comprising a plurality of nests of tubes, each of said nests being arranged to provide a longitudinally extending space, a shell for each nest of tubes, connections for passing circulating media through the respective nests of tubes in series, an ejector associated with one of the ends of each of said nests of tubes, the diffuser of each ejector being within the longitudinally extending spaces, and a connection from said one of the ends of one of 85 said nests of tubes to the ejector associated with another of said nests of tubes.

6. A device of the type described comprising a plurality of nests of tubes, each of said nests being arranged to provide a longitudinally extending space, a shell for each nest of tubes, connections for passing circulating media through the respective nests of tubes in series, an ejector associated with one of the ends of each of said nests of tubes, the diffuser of each ejector being within the respective longitudinally extending space, and directing means within each of the longitudinally extending spaces for directing gaseous media from said diffusers to the other of the respective ends of said nests of tubes. 95

7. A device of the type described comprising a plurality of nests of tubes, each of said nests being arranged to provide a longitudinally extending space, a shell for each nest of tubes, connections for passing circulating media through the respective nests of tubes in series, an ejector associated with one of the ends of each of said nests of tubes, the diffuser of each ejector being within the longitudinally extending spaces, directing means within each of the longitudinally extending spaces for directing gaseous media from said diffuser to the other of the respective ends of said nest of tubes, and a connection from said one of the ends of one of said nests of tubes to the ejector associated with another of said nests of tubes. 105

8. A device of the type described comprising a plurality of nests of tubes, each of said nests being arranged to provide a longitudinally extending space, a shell for each nest of tubes, connections for passing circulating media through the respective nests of tubes in series, an ejector associated with one of the ends of each of said nests of tubes, the diffuser of each ejector being within the longitudinally extending spaces, directing means within each of the longitudinally extending spaces, 115

tudinally extending spaces for directing gaseous media from said diffuser to the other of the respective ends of said nest of tubes, a connection from said one of the ends of one of said nests of tubes to the ejector associated with another of said nests of tubes, and baffles disposed within said nests of tubes for directing gaseous media in a tortuous course through said nests of tubes.

10. In apparatus of the character described, the combination of a feed water heater of the surface type including inlet and outlet water compartments at one end, a cylindrical nest of tubes for passing feed water outwardly from the inlet compartment and backwardly to the outlet compartment, said nest of tubes defining a longitudinally extending space, an ejector having its diffuser extending within and discharging into said space, and separate outlet means for media condensed in the heater and for non-condensed media.

10. In apparatus of the character described, the combination of a feed water heater including superposed inlet and outlet water compartments, pairs of tubes communicating with the respective compartments and communicating at their respective ends remote therefrom, said pairs of tubes being arranged to define a longitudinally extending space, a shell enclosing said pairs of tubes, and an ejector having its diffuser extending within and discharging into the said space.

11. In apparatus of the character described, the combination of a feed water

heater including vertically superposed inlet and outlet water compartments, pairs of tubes communicating with the respective compartments and communicating at their respective ends remote therefrom, said pairs of tubes being arranged to define a longitudinally extending space, a substantially vertically extending shell arranged to enclose said pairs of tubes, and an ejector having its diffuser within the said space.

12. In apparatus of the character described, the combination of a feed water heater of the surface type including inlet and outlet water compartments at one end, a nest of tubes for passing feed water outwardly from the inlet compartment and backwardly to the outlet compartment, said tubes being arranged to define a longitudinally extending space, an air ejector having its diffuser entering the heater and discharging into said space in the direction of said compartments, an outlet for non-condensed media associated with the end of the heater remote from the water compartments, means connected to the discharge end of the diffuser and arranged in said space and extending toward the water compartments for confining media discharged from the diffuser, baffle means arranged between the discharge end of the last-named means and said outlet, and an outlet for condensed media.

In testimony whereof, I have hereunto subscribed my name this 2nd day of July, 1924.

HENRY LEWIS GUY.
